A. TOURTAS.
DANCING DOLL TOY.
FILED MAY 14, 1921.

Patented Jan. 30, 1923.

1,443,770

UNITED STATES PATENT OFFICE.

ANASTASIOS TOURTAS, OF CHICAGO, ILLINOIS.

DANCING-DOLL TOY.

Application filed May 14, 1921. Serial No. 469,583.

To all whom it may concern:

Be it known that I, ANASTASIOS TOURTAS, a subject of the King of Greece, and a resident of Chicago, Cook County, and State of Illinois, have invented certain new and useful Improvements in Dancing-Doll Toys, of which the following is declared to be a full, clear, and exact description.

This invention relates to dancing doll 10 toys and its principal object is to provide a toy which is interesting, entertaining and attractive. Another object is to provide a toy which embodies an articulated figure simulating a human being, with means for 15 actuating the toy in a manner simulating more nearly the dancing steps and poses of human beings while dancing. The invention consists in a toy, embodying an articulated figure simulating a human being 20 mounted on a post or standard, and provided with a flexible connection which is taken hold of and given a series of jerks to impart the movements to the toy figure. The invention further consists in the several 25 novel features hereinafter fully set forth and claimed.

The invention is clearly illustrated in the accompanying drawing, in which:

Fig. 1 is a view partly in side elevation 30 and partly in central, vertical section of a dancing doll toy embodying a simple form of the present invention; Fig. 2 is a horizontal section taken on line 2—2 of Fig. 1 and Fig. 3 is a fragmental, detail side elevation of a certain guide member for the doll supporting post or standard.

Referring to said drawing, the reference character 5 designates a box or base having a door 6 hinged to its open front by hinges 40 7 and provided with a latch 8 whereby it may be secured in closed position. In the top 9 and bottom 10 of the box is secured a vertically extending guide member 11 which extends between said top and bottom and 45 for convenience in construction, is let into recesses or depressions formed in the opposing faces of said top and bottom 9, 10. Said guide member is preferably in the form of a tube, and intermediate its ends it is provided 50 with an outlet opening 12 in which is secured an eye member or loop 13, preferably formed of a piece of wire, bent into a loop and secured to the guide member 11, as for instance by wrapping the wire around it. 55 The eye or loop 13 projects into the outlet opening 12 and forms a smooth bearing sur-

face for an actuating cord 14, as will be presently explained. An opening 15 in the door, in line with the eye 13, affords an outlet through the box for the cord, whereby 60 it may be taken hold of at one side of the box in manipulating the toy figure.

In the guide member 11 is a post or standard, preferably in the form of a wooden stick 17, which projects out through a 65 hole in the top of the box above the guide member 11, and to the bottom of said post is secured the flexible member 14, which may comprise a cord, string or the like, which extends through the eye member 13 and may 70 lead out through the opening 15 in the door 6. Obviously, the post 17 may be reciprocated by jerking the cord 14.

Removably secured upon the upper end of said post 14 is an articulated Figure 19 75 (here shown in the form of a toy doll), in which the legs 20 are flexibly connected to the body portion 21 by strings, twine, cord or the like 22. Preferably, the doll is clothed with a skirt 23 that covers the joints 80 between the body and legs. A vertical socket 24 formed in the body of the doll, receives the upper end of the post 17. The doll may be readily detached from the post, and the post removed from the guide tube 85 for the purpose of storage or transportation. In assembling the parts, the end of the post having the cord fastened thereto, is inserted into the guide member, and the cord pulled out through the eye 13 by any 90 suitable hook and led out through the opening 15 in the door 6. The doll 19 is then placed on the top of the post 17 and the toy is ready for use.

The cord 14 is taken hold of and given a 95 series of jerks, and to obtain the best results, simulating a person, in the act of dancing, the jerks are made in time to music. In the drawing, the doll is shown in full lines in a position in which its feet are free from the 100 top of the box, as though in the act of jumping or hopping, and in dotted lines, it is shown in a position with its legs crossed, resting on the top of the box, as though making a bow. By properly manipulating the 105 cord, the feet may be made to dance on the top of the box, and because of the flexible connection, with the post and its unrestricted movement in the tube, the doll may be moved up and down as desired, and as the 110 post is free to rotate back and forth in the tube, the doll is free to turn and does turn

back and forth when the cord is manipulated. The top of the box acts as a platform for the doll to dance on.

I claim as new and desire to secure by 5 Letters Patent:

1. A toy comprising a base having a platform, a tubular guide member extending down from said platform, and having an outlet opening in its side, a doll figure, a reciprocal and revolute post supporting said doll figure and extending into said tubular guide member, and a flexible connection secured to said post and extending out through said outlet opening in the guide member, said flexible connection forming means whereby said post and doll figure may be manipulated.
2. A toy comprising a base having a platform, a tubular guide member, extending down from said platform, and having an outlet opening in its side, an articulated doll figure, a reciprocal and revolute post supporting said doll figure, and extending into said tubular guide member, and a cord secured to said post and extending upward from its place of connection with said post, and out through said outlet opening, and furnishing means whereby said post and doll figure may be manipulated.
3. A toy comprising a base having a platform, a tubular guide member, extending down from said platform, and having an outlet opening in its side, a wire loop secured to said guide member at said outlet opening, an articulated doll figure, a reciprocal and revolute post supporting said doll figure, and extending into said tubular guide member, and a cord secured to said post and extending upward from its place of connection with said post, and out through said outlet opening, and loop and furnishing means whereby said post and doll figure may be manipulated.

4. A toy comprising a box, the top of which acts as a platform, a tubular guide member extending down from said platform, and having an outlet opening in its side, a doll figure, a reciprocal and revolute post supporting said doll figure, and extending into said tubular guide member, and a flexible connection secured to said post and extending out through said outlet opening in the guide member, said flexible connection forming means whereby said post and doll figure may be manipulated.

5. A toy comprising a box, the top of which acts as a platform, said box having a door opening in its side and a door closing said opening, a tubular guide member extending down from said platform, and having an outlet opening in its side, a doll figure, a reciprocal and revolute post supporting said doll figure and extending into said tubular guide member, and a flexible connection secured to said post and extending out through said outlet opening in the guide member, said flexible connection forming means whereby said post and doll figure may be manipulated.

6. A toy comprising a box, the top of which acts as a platform, said box having a door opening in its side and a door closing said opening, said door having a slot formed therein, a tubular guide member extending down from said platform, and having an outlet in its side, a doll figure, a reciprocal and revolute post supporting said doll figure and extending into said tubular guide member, and a flexible connection secured to said post and extending out through said outlet opening in the guide member, and slot in the door, said flexible connection forming means whereby said post and doll figure may be manipulated.

ANASTASIOS TOURTAS.
